(57) **CLAIM**

We claim the ornamental design for a vending machine, as shown and described.

DESCRIPTION

FIG. 1 is a front perspective view of a vending machine, in accordance with our new design;

FIG. 2 is a front elevation view of the vending machine of FIG. 1;

FIG. 3 is a top plan view of the vending machine of FIG. 1; FIG. 4 is a bottom plan view of the vending machine of FIG. 1;

FIG. 5 is an enlarged left side elevation view of the vending machine of FIG. 1; and,

FIG. 6 is an enlarged right side elevation view of the vending machine of FIG. 1.

The broken lines depict unclaimed environmental subject matter and form no part of the claimed design.
